UNITED STATES PATENT OFFICE

2,519,398

WIRE CLOTHESPIN

Charles S. Read, New Smyrna Beach, Fla., assignor of one-third to Carl Anker, Edgewater, Fla.

Application July 31, 1945, Serial No. 607,957

2 Claims. (Cl. 24—139)

1

The object of this invention is to provide a wire clothespin made from a length of rust proof resilient wire characterized by a looped portion serving both as a handle and a means of suspension on a clothes line and a double looped portion at one end of the handle forming a central notch for wedging clothes on the line and a transverse notch for otherwise cooperating with clothes to hold them in suspended position.

Another object of my invention is to furnish a wire clothes pin which may be applied to and detached from the line at will and allowed to remain thereon until required for service in the "hanging out" of a washing of clothes and is capable of use for supporting garments in either position of suspension in which the pin per se may assume.

A further object of my invention is the provision of a wire clothes pin which is not only simple in its construction but is efficient and reliable in its operation and is inexpensive as an article of manufacture.

To these and other ends my invention comprehends further improvements all of which will be set forth in the accompanying specification, the novel features thereof being set forth in the appended claims.

In the drawings:

Figs. 1 and 2 are front and rear views in elevation showing a clothes pin embodying my invention.

Fig. 3 is a side view thereof.

Fig. 4 is a view similar to Fig. 1 showing the pin in the reverse position suspended from a clothes line, and

Fig. 5 is a cross sectional view taken on the line 5—5 of Fig. 2.

Similar reference characters in the several illustrations indicate similar parts.

In carrying out my invention I form the pin with a body or handle portion 1 made of a loop comprising the parallel side bars 2 and 3 connected at the bottom by the arcuate portion 4. One of these side bars is provided with a latch through which the clothes line may be passed into and out of the loop portion of the handle. Since the clothes pin is made of a single piece of wire I conveniently form the latch by overlapping the two ends of the wire a short distance. If desired one of these ends may be flattened and given a concave form on its inner side, as indicated at 5, to receive the other overlapping extremity 6 of the wire. This latch is preferably located adjacent to the arcuate end 4 of the loop.

At the opposite end of the loop 1 is the head or

clothes gripper which may be used to bind portions of garments, or other articles, directly onto the clothes line, indicated by 7 in Figs. 1 and 2, or to receive articles when the position is reversed as shown in Fig. 4.

Observing Fig. 1, it will be seen that the side bars 2 and 3 are curved inwardly at 2^a and 3^a forming a neck of a width somewhat less than that of the main loop 1. From this point the bars flare laterally to the points 2^b—3^b where they are given reverse or reentrant bends and extend downwardly in substantial parallelism into the area of said neck. These reentrant portions of the bars, indicated as 2^c and 3^c, form pincers. They are spaced apart slightly at their lower ends where they are curved in opposite directions in accordance with the sides of the neck. This enables them to embrace the clothes line 7 and facilitate its entrance between the bar portions 2^c—3^c together with the portion of the clothes that may be suspended on it.

The pincers portions of the arms formed by portions 2^c, 2^e and 3^c, 3^e, respectively, are bowed in a transverse direction (see Fig. 3) so that their lower ends stand forward of the plane of the bars 2 and 3 and in close proximity with bars 2 and 3 at the point where the latter curve inwardly to form the neck. Thus it will be seen that a pincers action may also be had at two additional points, viz.; between the bar 2 and the bottom end 2^d of the head loop and between the bar 3 and the lower end 3^d of its head loop.

The required resiliency or spring action necessary to firmly grasp the clothes line and clothes at the point thereon where the pin is applied is accomplished by reversely bending the wire upwardly (Fig. 2) at the extremities 2^d—3^d to form an upwardly standing loop formed by the portions 2^e—3^e which are connected at their tops by the bend 10. It will also be noticed from Fig. 3 that the arm portions 2^e—3^e are bowed outwardly, i. e. in a direction opposite to the curve given to the parts 2^d—3^d to throw the bend 10 away from the plane of the top bends 2^b—3^b so that there is thus provided between these elements another throat for clamping clothes.

Another short explanation which will enable the construction to be readily visualized is this: A wire of given length is bent at a mid point into a central loop comprising portions 2^e—3^e spaced apart a distance approximately the diameter of a clothesline, the apex 10 of the loop being somewhat smaller than said diameter. The sides of this loop are next bent rearwardly upon themselves, at the bottom portions 2^e—3^e a distance

sufficiently removed from its apex 10 to provide the adjacent pairs of arms 2^c—3^c, with the necessary lateral resiliency to enable them to firmly grip a clothes line. Next, the arms 2^c—3^c are bent laterally to form the loops 2^b—3^b. In so bending the sides they extend transversely to the plane of the loop, and in rear thereof. The then remaining free ends of the wire are bent laterally as shown in Figs. 1, 2 and 4 to form the neck and downwardly the distance desired to form the handle, their extremities being located in an overlying fashion to form the latch which permits the pin to be engaged with the clothes line.

For hanging the heavier articles of a day's washing, such as those which are customarily thrown in part over the line, the pins will be used in the position shown in Figs. 1 and 2. At other times, for lighter articles and for lengthy articles such as sheets or table cloths which require intermediate supports, the pins may be reversed, as shown in Fig. 4, and the articles secured in one or another of the pincers before mentioned. The grippers last referred to also perform a useful function when the pins are used in the first described position as they enable smaller garments to hang over heavier articles at their points of support, thus increasing the holding capacity of a clothes line.

The claimed invention is:

1. A wire clothes pin having outer side bars the ends of which are bent inwardly and turned back against said outer bars to form inner side bars in the space between the outer bars, said inner bars being integrally joined and reversely bent forwardly at a midpoint upon themselves to form clothes line gripper arms, said arms having a flared opening between their lower ends permitting the entrance of a clothes line to be gripped

therebetween, each of said arms being in close proximity with its contiguous outer bar and co-operating therewith to form a pincer.

2. A wire clothes pin having outer side bars the ends of which are bent inwardly and turned back against said outer bars to form inner side bars in the space between the outer bars, said inner bars being integrally joined and reversely bent forwardly at a midpoint upon themselves to form clothes line gripper arms, said arms having a flared opening between their lower ends permitting the entrance of a clothes line to be gripped therebetween, each of said arms being in close proximity with its contiguous outer bar and co-operating therewith to form a pincer, said side bars having overlapping free ends forming a latch near the end of the clothes pin opposite said gripper arms for the entrance and exit of a clothes line into and out of the clothes pin.
